MODULATION SYSTEM

Charles F. Sheaffer, Tulsa, Okla., assignor to
Radio Corporation of America

Application September 13, 1940, Serial No. 356,689

11 Claims. (Cl. 179—171.5)

My invention relates to modulation systems and, more particularly, to systems wherein a signal representing intelligence or other signal is impressed upon an outgoing carrier wave by causing the frequency thereof to depart more or less from a mean frequency determined by an oscillation generator.

It is an object of my invention to provide an oscillator-modulator of the frequency shift type that shall be extremely stable in operation.

Another object of my invention is to provide a frequency-shift modulation system that shall be substantially devoid of amplitude modulation effects.

Other objects will be apparent from the following description of a preferred embodiment of my invention, when read in connection with the accompanying drawings wherein:

Fig. 1 is a block diagram, exemplifying a frequency shift modulation system comprising a preferred embodiment of my invention;

Fig. 2 is a schematic circuit diagram exemplifying an oscillator-modulator unit comprising a preferred embodiment of my invention;

Fig. 3 is a graph, wherein frequency is plotted against time of operation and indicating by curve *a* the frequency stability of my improved oscillator *per se* and by curve *b* the frequency stability of the oscillator-modulator unit;

Fig. 4 is a plot of the equation, referred to hereinafter, indicating the theoretically attainable linearity, and,

Fig. 5 is a graph indicating the measured frequency modulation characteristics of the unit by the curve *a* and after proper compensation thereof by the curve *b*.

Before explaining my invention in detail, it will be helpful to refer briefly to systems heretofore in use. There are three main types of frequency modulation transmitters, differing from each other in the specific method utilized to produce the frequency-shift. (1) The Armstrong method described by D. L. Jaffe in Proc. I. R. E., April, 1938, wherein phase shifts are produced by combining amplitude modulation side bands with a carrier of proper relative phase and the resulting frequency deviations are multiplied a number of times to obtain the proper modulation band and output frequency; (2) the system recently developed by Robert E. Shelby, described in Electronics, February, 1940; and (3) systems utilizing the so-called reactance tube circuit for controlling the frequency of an oscillator.

Shelby's system makes use of a cathode ray 55 means of which the output from my improved

tube with a specially constructed target, and converts amplitude modulation into phase modulation. It is possible, with that system, to produce phase deviations many times greater than is possible by Armstrong's system. As a result, fewer frequency doubling stages are necessary and much better frequency stability is claimed.

A system of the third type was described by I. R. Weir in the General Electric Review, May 10 and June 1940. It utilizes a reactance tube modulated oscillator of moderately high frequency and requires one doubler stage for deriving the proper modulation band and output frequency. The inherent instability of the oscillator frequency caused by the associated reactance tube modulator makes it imperative that some means of stabilizing the frequency be employed. Present practice is to beat down the frequency from some point in the circuit by means of a highly stable crystal controlled oscillator and to apply this derived frequency to an automatic frequency control device similar to the devices utilized for stabilizing the tuning of broadcast receivers. For transmitting purposes, it is highly important that the A. F. C. circuit have a substantially linear output characteristic throughout the range of applied frequency deviation. If it does not have such a characteristic, variations in carrier frequency will result from the application of non-sinusoidal modulation potentials. This limitation dictates the minimum frequency to which the signal may be beaten down and, therefore, limits the stability obtainable.

Accordingly, another object of my invention is to provide a system for producing frequency modulation, through the utilization of reactance tubes, that shall not require an automatic frequency control circuit for stabilization.

Another object of my invention is to provide an oscillator-modulator unit of the type utilizing reactance tubes, wherein the effect of one of the reactance is so balanced against the effect of another reactance tube that in phase changes in the mutual conductance thereof will cause no appreciable change in the oscillator frequency.

Having in mind the defects of reactance tube systems heretofore known, my invention involves the use of an oscillator working at a relatively low base frequency and at least two reactance tube modulators associated with the output circuit thereof and controlled in push-pull relation, so to speak, by the signal source. In addition, I utilize a combination of a balanced modulator, a mixer and a tripler, connected in cascade, by

oscillator-modulator is raised to the radiation frequency without resorting to a large amount of frequency multiplication which, of course, would also multiply the slight amount of instability inherent in the oscillator per se.

Inasmuch as one object of my invention is to dispense with A. F. C. circuits, another object ancillary thereto is the provision of a highly stable low frequency oscillator.

Digressing somewhat, regardless of the method utilized to produce frequency modulation, the amount of control which can be brought to bear is directly proportional to the maximum susceptance that can be produced by the control device. Accordingly, any means which may be utilized to increase the ratio I_x/E_0 , where I_x is the current through the controllable reactance and E_0 is the voltage across the oscillator tuned circuit, will increase the frequency control ability of the modulator. Another object of my invention, therefore, is to provide an oscillator-modulator which would be adaptable to the use of small values of E_0 and, at the same time, permit high values of I_x to be obtained. A related object of my invention is to provide an unit that comprises sufficiently low values of L_0/C_0 in the tuned circuit for maintaining good frequency stability, without too severely limiting the modulation capability.

Incidentally, in explaining the principles involved herein, it is necessary to call attention to some of the inherent properties of the 6SA7 modulator tubes. This type of tube has two control grids, the grid nearest the cathode, referred to in the claims as the excitation grid, controls the total emission and, hence, the current flow in both the screen grid and plate circuits, and another control grid, referred to in the claims as a modulation grid, which controls the current in the plate circuit, but has no substantial effect on the total emission current. It is a characteristic of this type tube for the screen grid to draw the major portion of the emission current. Since the voltage supplied to the excitation grid of each modulator is substantially constant in value, the emission currents and, hence, the automatic bias of each tube will also be constant, even with relatively high values of cathode biasing resistance, and since the modulation grids can cause no substantial change in the respective emission currents, the biases of the two modulators will remain constant during process of modulation. If a current change accidentally occurs, said change will cause a change in the cathode resistor voltage drop which will be applied to both grids simultaneously and which will be of proper polarity to counteract the current change. The great amount of degenerative action exemplified in claim 21 is, therefore, the result of the use of relatively high values of cathode biasing resistance in the modulator tubes and due to the fact that a current change in a given tube feeds back a degenerative voltage into both its control grids.

Referring now to Fig. 2 of the drawings, my preferred oscillator comprises two thermionic tubes, a 6SJ7 designated V_1 , and a 6F6, designated V_2 . The tube V_1 supplies energy to a tuned output comprising an inductor 1 and a tuning capacitor 3 . Plate potential of about 6 to 10 volts is supplied to V_1 from a 250 volt D. C. source over a 50,000 ohm resistor 5 and a choke 7 of approximately 80 mh. inductance. The amplitude of oscillation, therefore, is approximately equal to the plate supply potential.

The grid of the 6F6 is fed directly from the tuned circuit, comprising condenser 3 and inductance 1 , and acts as a class A amplifier, and the amplified oscillations, inverted in phase, are fed back to the control grid of the 6SJ7 and to the grid networks of the reactance tubes V_{x1} and V_{x2} connected in shunt relation to the tuned oscillator circuit. The action of the reactance tubes will be explained later; however, it may be well to point out that they exert their greatest effect when connected across the complete tuned circuit.

Each of the reactance tubes is of the 6SA7 type, the space-current path in each tube being disposed in shunt relation to the tuned circuit of the oscillator. The reactance tubes are supplied with plate potential from the 250 volt source, a choke 9 of 30 mh. inductance being serially included in the supply circuit.

The control grids of the reactance tubes are supplied with modulating potentials in push-pull manner, from the secondary winding 11 of an audio frequency transformer 13 . For balancing purposes, the resistance element 15 of a potentiometer is connected across the secondary winding of the transformer and the movable contact 17 thereof is connected to a conductor 19 common to the cathodes of all of the tubes.

It is possible, by making the assumptions usually permissible in an analysis, to set up and solve an equation for the frequency of oscillation of this circuit. This has been done by equating the voltages acting in it and solving for the frequency. To determine the effect of resistance that might be shunted across the tuned circuit, such a resistance is included in the equation and designated R . R_0 takes into account the ratio of resistance to reactance, or Q of the coil, and R_2 is the effective load resistance in the plate circuit of the 6F6 tube. The equation for the frequency is:

$$(1) \quad f = \frac{1}{2\pi} \times \sqrt{\frac{1 - R_0 R_2 G_m (G_{m2} K + R_0/R)}{L_0 C_0}}$$

The conditions required for sustained oscillations are represented by the equation:

$$(2) \quad L_0 C_0 = \frac{R_0}{G_{m1} G_{m2} R_2 K - 1/R}$$

In any oscillation generation system, frequency instability may arise from either or both of two sources, i. e., (a) variations in the tuned circuit values, caused by temperature and/or humidity changes and (b) variations in tube operating conditions, which result from supply voltage deviations, temperature changes, aging of tubes, etc.

Frequency drifts resulting from the first cause are not extreme at the intermediate frequencies and may partly be balanced out by compensating capacitors. The second cause cannot entirely be eliminated, but it can be minimized by choosing such circuit values and operating conditions that will make the second term under the radical in Equation 1 insignificantly small. This may be done by limiting the amplitude of oscillation, by selecting a tank circuit having a sufficiently high Q and by effectively eliminating or reducing to the lowest possible minimum, admittances which act in shunt to the tank circuit, since according to Equation 2 any admittance across the tank circuit will require a higher mutual conductance in order to meet the conditions for oscillation, which in turn will increase the magnitude of the second term under the radical in Equation 1, thereby increasing the instabilities resulting from that term.

The circuit constants indicated in Figure 2 of the drawings, though not critical, provide an oscillator having a high degree of frequency stability. Figure 3 is a graphical representation of the performance of the circuit during a test run of six hours. Curve *a* represents the performance of the unit with the reactance tubes inactive, i.e., the performance of the oscillator per se. The actual stability is perhaps more truly reflected in the fact that a 10% change in both filament and plate voltages gave rise to a frequency change of less than three cycles per second from the base frequency of 350 kilocycles.

A very important feature of my invention resides in so connecting the reactance tubes into the circuit that in-phase changes in the mutual conductance thereof, occasioned by any extraneous cause, will automatically offset each other and cancel out, thus producing no change in the frequency of oscillations generated. Such a result I found possible for the reason that a reactance tube may be caused to introduce the effect of either capacity or inductance by proper selection of the phase of the grid excitation thereof.

Referring once more to Fig. 2 of the drawings, it will be noted that the preferred embodiment of my invention comprises two reactance tubes, V_{x1} and V_{x2} , the first tube being for the purpose of introducing inductance and the second, capacity, into the frequency-determining tank circuit of the oscillator, as will be explained in more detail.

It can be shown theoretically that if such a system is so adjusted that the reactances, at the oscillation frequency, of the two reactance tubes and their associated networks are equal, changes in mutual conductance thereof that occur in phase will cause no change in the oscillator frequency, because one reactance tube will produce a reduction in tank circuit inductance and other will effect a proportionate increase in tank circuit capacity and vice versa. The net effect, of course, of the in-phase changes in mutual conductance is zero change in oscillation frequency. The in-phase variations in mutual conductance that arise in actual operation are usually the result of changes in supply potentials, aging of the tubes, temperature changes, etc., and they have substantially no effect upon the frequency stability of the system.

The general performance of the reactance tubes may be described as follows:

The voltage across the plate load resistor 21 of the 6F6 tube is $-NE_0$, N being the voltage amplification obtained from the 6F6. This voltage is applied to the phase shifting networks supplying the grids of the two reactance tubes. The said networks, respectively, comprise a resistor 23 and an inductor 25 for the tube V_{x1} , and a resistor 27 and a capacitor 29 for the tube V_{x2} . The value of the resistance, R_s , is exceedingly greater than the reactance values of L_s and C_s and, therefore, the networks cause phase shifts approximating 90 degrees.

Let the current in each of the phase shifters be:

$$I_s = \frac{-NE_0}{R_s}$$

The voltage applied to the grid of V_{x1} will then be:

$$E_s = \frac{J\omega L_s(-NE_0)}{R_s} = \frac{-J\omega L_s N E_0}{R_s}$$

and the plate current will be:

$$I_x = \frac{-j\omega L_s N G_{mz1} E_0}{R_s}$$

The reactance in shunt with the tuned circuit due to V_{x1} will be:

$$\frac{E_0}{I_x} = \frac{jR_s}{N G_{mz1} \omega L_s} = j\omega L_x$$

or

$$L_x = \frac{R_s}{N G_{mz1} L_s \omega^2}$$

V_{x1} , therefore, acts like an inductance, the value of which is inversely proportional to the square of the frequency. The apparent reason for that fact is that the frequency change effected by the reactance tube itself is instrumental in causing an increase in the voltage supplied to its grid. This is the opposite of what would happen if the voltage supply for the phase shifting network were in phase with the tank circuit voltage.

An analysis of the action of the tube V_{x2} , foregoing, yields:

$$C_x = \frac{N G_{mz2}}{C_s R_s \omega^2}$$

Such tube, therefore, functions to introduce the effect of capacity, which is also inversely proportional to the square of the frequency.

I have derived a reasonably simple equation that expresses the frequency of oscillation, assuming that in the absence of a signal, sustained oscillations occur at the anti-resonant frequency resulting from the combined reactance of the tank circuit and the reactance tubes.

Such equation is as follows:

$$F = \frac{1}{2\pi} \times \sqrt{\frac{N G_{mz2} L_0 - R_s C_s}{N G_{mz1} L_0 L_s C_s - L_0 C_0 C_s R_s}} \quad (3)$$

The characteristics of the above equation are exemplified by Figure 4 of the drawings. From an inspection of the graph, it will be apparent that the modulating potentials must be applied to the control circuits of the reactance tubes in a push-pull manner. The plot, therefore, is drawn from the points obtained by assuming that the two mutual conductances vary linearly, but in opposite directions with respect to each other.

Although the graph in Figure 3 is not exactly straight, it is a fair approximation, provided the frequency interval does not exceed plus or minus 50 kilocycles when utilizing an oscillator frequency of 350 kilocycles. The modulation characteristic may be made substantially linear over the mentioned range by adjustment of the reactance tube grid biases in conjunction with proportioning of the modulation voltage supplies for the two tubes. For the latter purpose, the potentiometer shunted across the secondary of the modulation transformer, is utilized.

Figure 5 shows graphically the result of two series of measurements made on an operating oscillator-modulator constructed according to my invention. Curve *a* was drawn by plotting the frequency deviations which resulted from the application of steps of voltage of equal and opposite potential to the grids of the modulators and is similar to the curve obtained by plotting Equation 3. Curve *b* was obtained by plotting maximum deviations vs. sine wave modulating voltage and, therefore, is an indication of the extent of linearity that may be obtained.

Although I have mentioned 350 kilocycles as

the preferred oscillator frequency, it is not to be inferred that my invention is limited to that exact number. At frequencies lower than the preferred frequency, it progressively becomes more difficult to obtain satisfactory modulation at higher modulation frequencies because of the resulting increase in tank circuit impedance at the modulation frequencies that occasions voltage fluctuations to be fed into the oscillator grid circuit, disturbing the operation thereof. There are methods by which this difficulty may be avoided, but in view of the more exacting side band filter requirements in the mixer output, they are not included herein.

The circuit adjustments necessary for making the frequency independent of the in-phase variations in mutual conductance of the reactance tubes may be obtained from Equation 3 by setting the ratio of the terms in the numerator equal to the ratio of the terms in the denominator. The required conditions then are:

$$L_g C_g = L_0 C_0, \text{ and } G_{mx1} = G_{mx2}.$$

The frequency of oscillation is then equal to the fundamental frequency of the tuned circuit.

In an article published by me in Proc. I. R. E., February, 1940, I have shown that if 180° phase difference exists between the oscillator tank circuit voltages and the voltage supply for the reactance tube network, an adjustment may be found which would result in neutralizing the resistance that otherwise would be shunted across the tuned circuit because of the plate resistance of the reactance tubes. This is an important feature of my invention because it minimizes amplitude modulation of the oscillator and effectively eliminates undesirable loading of the tuned circuit.

The plate circuit of the 6F6 tube in the oscillator includes a transformer 31 and a capacitor 33 connected in shunt relation to the load resistor 21. The inductance of the transformer together with the adjustable capacitor provide means for adjusting the phase of the voltage drop to the proper value. The load resistor 21 furnishes sufficient damping to render negligible phase shifts resulting from frequency deviations within the modulation band. The output connection is made from the secondary winding of the transformer 31.

It is necessary to thoroughly by-pass the cathode resistor in order to prevent it from acting as a frequency-modulation to amplitude-modulation converter, thereby producing unwanted amplitude modulation of the reactance tube grid supply. Such action on the part of the 6F6 tube would result in accentuating any non-linearity of the frequency modulation characteristic.

The circuit values in the drawings, if followed closely will give rise to an extremely stable oscillator-modulator; it is not to be inferred, however, that my invention cannot be practiced through the utilization of circuit constants differing from those shown. The actual unit, under test, maintained its assigned frequency over a long period to within plus or minus 300 cycles.

Referring now to Fig. 1, the manner in which the frequency modulated carrier wave may be obtained is exemplified by block diagrams. The output from my oscillator-modulator is mixed in a balanced modulator 35 with the output from a 3300 kc. crystal controlled oscillator 37. The upper sideband, which is 3650 kc. plus the modulation band of plus-minus $33\frac{1}{3}$ kc. is then selected and mixed with the output from a 10,083 kc. crystal controlled oscillator 39 in a conventional

mixer 41. The upper sideband is again selected, thereby deriving a frequency of 13,733 kc. which is fed into a conventional tripler 43 which provides the carrier frequency and plus-minus 100 kc. modulation capability. A power amplifier 45 may be interposed between the tripler and the radiator.

If we assume that a stability of 10 cycles per megacycle can be obtained from the crystal controlled oscillators, and that the modulated oscillator can be maintained to within plus-minus 300 cycles of its base frequency, an overall frequency drift of plus-minus 1130 cycles is possible, which is but $\frac{1}{4}$ of .01% at 41 megacycles. I have checked the system repeatedly over extended periods of time and the results indicate that a normal stability of better than .01% can be easily maintained at 41 megacycles, without the use of any sort of automatic means for continuously re-adjusting the oscillator frequency. One of my experimental runs is graphically shown by curve b in Fig. 3, which indicates that the frequency is substantially constant subsequent to a warm-up period of 15 minutes.

It is my personal belief, based upon numerous experiments and check runs, that the stability of my improved system is much better than that claimed for other systems of frequency modulation that utilize reactance tube modulation and automatic frequency control devices of the discriminator type. My system compares favorably, in both simplicity and stability, with the best of the other systems now in use. It is to be understood, nevertheless, that if performance substantially that of a crystal controlled oscillator is necessary, an automatic frequency control device of conventional type may be utilized in conjunction with the oscillator-modulator, which may be so arranged that it will correct the oscillator frequency during intervals of low modulation.

Another advantage of my invention resides in the fact that substantially no amplitude modulation occurs and the stability is independent of the wave form of the modulating voltages.

Although I have illustrated and described a specific embodiment of my invention, modifications will be apparent to those skilled in the art to which it pertains. My invention, therefore, is not to be limited except insofar as is necessitated by the prior art and by the spirit of the appended claims.

I claim as my invention:

1. In a wave length modulation system, a wave generating means comprising a pair of electron discharge devices each having input and output electrodes, a tank circuit connected between the output electrodes of one of said devices, a coupling between said tank circuit and the input electrodes of the other of said devices, a coupling between the output electrodes of said other of said devices and the input electrode of said one of said devices, a pair of electron discharge tubes each having an anode, a cathode and a control grid, means coupling the impedances between the anodes and cathodes of said pair of tubes in shunt to said tank circuit, a phase shifting circuit including a resistance and an inductance coupling the output electrodes of said other of said devices to the control grid of one of said tubes, a phase shifting circuit including a resistance and a condenser coupling the output electrodes of said other of said devices to the control grid of the other of said tubes, and means for modulating the impedances of said pair of tubes in push-pull relation in accordance with signals.

2. In a wave length modulation system a source of oscillations including, a tank circuit, a tube generator having an anode electrode coupled to a point on said tank circuit and a grid coupled by phase reversing means to said point on said tank circuit, means for applying relatively low direct current potentials to the electrodes of said tube whereby oscillations of relatively low voltage are produced and set up in said tank circuit, and means for modulating the oscillations generated comprising a pair of reactance devices each having an anode and a cathode and a control grid, a coupling between the anodes of said devices and said first named point, a coupling between the cathodes of said devices and a second point on said tank circuit, phase shifting reactances coupled to the control electrodes of said reactance devices, connections between said phase shifting reactances and said phase reversing means, means for modulating the impedances of said pair of devices in push-pull relation in accordance with signals, and means for producing degeneration in said devices.

3. In a wave length modulation system, an electron discharge device oscillator having electrodes coupled with a tank circuit for generating oscillations of relatively low amplitude and substantially constant frequency, and means for modulating the wave length of the oscillations generated comprising a pair of electron discharge tubes each having an anode, a cathode and a control grid, means coupling the anodes of said tubes together and to a first point on said tank circuit, means coupling the cathodes of said discharge tubes together and to a second point on said tank circuit, a relatively large biasing resistance in a common circuit between the anode and cathode and grid and cathode of each of said tubes to produce degeneration in said tubes, phase reversing means coupled to said first point on said tank circuit, a phase shifter coupling the control electrode of each of said tubes to said phase reversing means whereby oscillations displaced by more than 90 degrees appear on the anode and grid of each tube, and means for modulating the impedances of said tubes in phase opposition in accordance with signals.

4. In a wave length modulation system an electron discharge device oscillator having a tank circuit for generating oscillations of relatively low amplitude, and means for modulating the wavelength of the oscillations generated including a pair of electron discharge tubes each having an anode, a cathode and a control grid, connections coupling the anodes and cathodes of said discharge devices in shunt to said tank circuit said connections setting up on said anodes oscillations of a first phase, an amplifier tube having input electrodes coupled to said tank circuit and excited by oscillations of said first phase, said amplifier tube having output electrodes, a variable condenser and an inductance in parallel coupled to said output electrodes of said amplifier, said parallel inductance and condenser serving to adjust the phase of the voltages in said parallel arrangement, a phase shifter coupling the control electrode of each of said tubes to said parallel arrangement, and means for modulating the impedances of said tubes in phase opposition in accordance with signals.

5. In a wave length modulation system, a wave generator comprising a pair of electron discharge devices each having input and output electrodes, a tank circuit coupled with the output electrodes of one of said devices and with the input electrode

of the other of said devices, an output circuit comprising an inductance, a capacity and a resistance effectively in parallel coupled with the output electrodes of said other of said devices, said other of said devices serving to reverse the phase of the oscillations in said output circuit relative to the phase of the oscillations in said tank circuit, a pair of reactance tubes having input and output electrodes, means coupling the output electrodes of said reactance tubes in shunt to said tank circuit, a phase shifting reactance coupling the input electrodes of each of said reactance tubes to said output circuit, and means for modulating the impedances thereof in phase opposition in accordance with signals.

6. In a wave length modulation system a tank circuit wherein high frequency oscillations, the wave length of which is to be modulated flow, a pair of electron discharge devices each having an electron receiving electrode, an electron flow control electrode and a cathode, means tying the electron receiving electrodes together and to a point on said tank circuit, means coupling the cathodes of said devices to a second point on said tank circuit, a phase reversing tube having input electrodes coupled to said first point on said tank circuit and having output electrodes, a phase shifting reactance coupling the output electrodes of said phase reversing tube to the electron flow control electrode in each of said devices, said phase shifting reactances being of different character whereby the oscillations on the electron receiving electrodes and flow control electrodes of the devices are displaced by more than 90°, and means for differentially modulating the impedances of said devices unequal amounts in accordance with signals.

7. A wave length modulation system including, a tank circuit wherein wave energy the wave frequency of which is to be controlled flows, a pair of electron discharge devices each having an anode, a cathode, and a control grid, a connection tying the anodes of said devices together and to a point on said tank circuit, a connection between the cathodes of said devices and a second point on said tank circuit, a wave amplifying and wave phase reversing tube having a control electrode coupled to said first point on said tank circuit and having a cathode coupled to another point on said tank circuit, said reversing tube having output electrodes, a phase advancing network coupling the output electrodes of said reversing tube to the control grid of one of said first named devices, a phase retarding network coupling the output electrodes of said tube device to the control grid and cathode of the other of said first named tubes, the couplings being such that the alternating current voltages on the anode and control grid of each tube are displaced by more than 90 degrees, and means for modulating the impedances of said tubes differentially in accordance with signals.

8. In a wave length modulation system, an oscillation generator including, a pair of electron discharge devices each having a control grid, an anode, and a cathode, a tank circuit coupled between the anode and cathode of one of said devices, a coupling between the anode of said one of said devices and the control grid of the other device and a feedback coupled between the anode of said other device and the control grid of said one device, a reactance tube having an anode, a cathode, and a control grid, a coupling between the anode of said reactance tube and the anode of said one of said devices, a coupling between the

cathode of said reactance tube and the cathode of said one of said devices, means for deriving from the anode of the other of said devices oscillations of the same phase as the oscillations on the control grid of said one of said devices, a phase shifting network coupling said last named means to the control grid of said reactance tube, and means for modulating the impedance of said reactance tube in accordance with signals.

9. Means for generating wave energy and controlling the wave length thereof including, a tank circuit, a generator tube having an anode and a cathode coupled together by said tank circuit, said generator tube having a control grid, circuit connections for deriving voltage of the generated frequency from the anode of said tube, and means for reversing the phase of the voltage and returning the voltage to the control grid of said tube to produce regeneration in said tube and tank circuit, a reactance tube having an anode, a cathode, and a control grid, a substantially direct coupling between the anode of said reactance tube and the anode of said generator tube whereby the phases of the generated voltages on the anodes are the same, a phase shifting circuit coupled to the control grid and cathode of said reactance tube, a coupling for impressing said reversed volt-

age on said phase shifting circuit, and connections for controlling the impedance of said reactance tube in accordance with variable control potentials.

10. A system as recited in claim 9 wherein said phase reversing means also amplifies the generated oscillations fed to said phase shifting circuit.

11. In combination, an oscillation generator having a tank circuit for adjusting the frequency of the generated oscillations, at least two reactance tubes, each having a space-current path and electrodes including a control grid associated with said path, means coupling the space-current paths in said tubes effectively in shunt to said tank circuit, connections for impressing variable control potentials in push-pull manner upon the control grids in said tubes, means for shifting the phase of the generated oscillations substantially 180°, and connections for additionally shifting the phase of said oscillations in different directions and impressing said oscillations of shifted phase simultaneously upon corresponding electrodes in said tubes, whereby frequency shift control may be attained and the resistance effect of the reactance tubes upon the tank circuit is minimized.

CHARLES F. SHEAFFER.
